(57) **CLAIM**

The ornamental design for the socket for temperature monitoring probe of patient monitor, as shown and described.

DESCRIPTION

FIG. 1 is a perspective view from one end of a socket for temperature monitoring probe of patient monitor showing our new design;

FIG. 2 is a top view thereof;

FIG. 3 is a bottom view thereof;

FIG. 4 is a first side view thereof;

FIG. 5 is a second side view thereof;

FIG. 6 is a first end view thereof;

FIG. 7 is a perspective view of the socket for temperature monitoring probe of patient monitor showing a non-connected state with an associated plug; and,

FIG. 8 is a perspective view of the socket for temperature monitoring probe of patient monitor showing a connected state with an associated plug.

The broken lines showing portions of the socket for temperature monitoring probe of monitor and environmental structure forms no part of the claimed design.
